UNITED STATES PATENT OFFICE.

HARRY L. JONES, OF GENEVA, ILLINOIS.

CORN-HARVESTER.

SPECIFICATION forming part of Letters Patent No. 429,311, dated June 3, 1890.

Application filed June 24, 1889. Serial No. 315,399. (No model.)

To all whom it may concern:

Be it known that I, HARRY L. JONES, a citizen of the United States, residing at Geneva, in the county of Kane and State of Illinois, have invented certain new and useful Improvements in Corn-Harvesters, of which the following is a full, clear, and exact description, that will enable others to make and use the same, reference being had to the accompanying drawings, forming a part of this specification.

This invention relates to improvements in that class of corn-harvesters wherein the cutting, carrying, and binding mechanism are mounted on suitable carriage or truck wheels and drawn by horses, the same consisting of certain novel features in the combination, arrangement, and operation of the several parts, as will be hereinafter set forth.

Figure 1 is a front elevation of a machine embodying my improved features; Fig. 2, a plan with some of the parts omitted. Fig. 3 is a side elevation and part section in plane 3, Fig. 1. Fig. 4 is a plan detail of one of the sickle-bars. Fig. 5 is an enlarged transverse sectional detail of the sickle-bars and parts. Fig. 6 is a broken-away rear elevation and part section, the rear framing-boards in which the apron-rollers are journaled being removed; and Fig. 7, a broken-away rear elevation with the framing-boards in place.

Referring to the drawings, 8 represents the different parts of the carriage-frame; 9 and 10, the carriage-wheels; 11, the draft-pole, and 12 the driver's seat.

The required motion is transmitted to the different working parts from the ground or driving wheel 9, which is mounted on the axle-shaft 13 (see Fig. 2) and provided with suitable bearings in the frame. The gear-wheel 14 is mounted on the wheel-shaft 13, and in turn engages with the pinion 15, mounted on the driving-shaft 16. The clutch-collar 17 rotates with the shaft 16 and is feathered thereon, so as to provide for a longitudinal movement when engaging with the companion clutch-collar 18, loosely mounted on shaft 16. A bevel gear-wheel 19 is rigidly mounted on the loose member 18 of the clutch-box and in turn engages with the bevel-pinion 20, rigidly mounted on the inner end of the counter-shaft 21. The clutch-collar 17

is provided with an annular groove 22, in which is pivoted one end of the angle shifting-lever 23, pivoted at 24 to the frame, as shown in Fig. 2. To the opposite end of angle-lever 23 is attached one end of the rod 25, the opposite end of said rod being connected to one end of the bell-crank lever 26, to the other end of which is connected the lower end of the rod 27, broken away in Fig. 2, but shown in Fig. 1. The upper end of rod 27 connects with the lower end of the bell-crank lever 28, (see Figs. 1 and 3,) to the upper end of which is attached the front end of the horizontal rod 29. The rear end of rod 29 is attached to the shifting-arm 30, one end of which is pivoted to the bracket 31 and is located under the seat and within convenient reach of the driver. The clutch mechanism 70 is shown disengaged.

Throwing the shifting-arm 30 over to the opposite position from that illustrated in Fig. 3 has the effect of bringing the clutch mechanism into a working engagement.

Upon and near the outer end of counter-shaft 21 is rigidly mounted the bevel gear-wheel 32, engaging with the corresponding pinion 33, mounted on shaft 34. (Shown in Figs. 1 and 2.) A companion shaft 35 is provided with suitable bearings in the rocking bracket 36, pivoted at 37 to the fixed supporting-lugs 38 and 39, secured to the frame-work. The companion shafts 34 and 35 are connected by the tumbling-rod 40, the respective coupling ends of each being provided with the gimbal-joint 41. The outer end of the gimbal-shaft 35 has the pinion 42 mounted thereon, as indicated by dotted lines in Fig. 1.

The bevel gear-wheel 43 is mounted on the vertical reel-shaft 44 and engages with pinion 42. The lower end of the reel-shaft is journaled and supported in the end of the rocking bracket 36. The relative position of these parts is shown in dotted lines on account of the inner dividing-board 45. By this arrangement the desired rotary motion is transmitted to the reel-shaft and the reel 46 mounted thereon.

The reel is adapted to have a vertical adjustment on its shaft—that is, raised or lowered in accordance with the height of the stalks of corn. This adjustment is accomplished through the medium of the angle-

lever 47, the bifurcated end of which is attached to the loose collar 48 on the reel-hub 49, as shown in Figs. 1 and 3. The handle part of lever 47 is mounted on the pivot-bolt 50, which passes through the toothed sector 51 and the hand-lever 52. The sector 51 is also fastened to lever 52 at 53, and moves therewith when the same is shifted. Lever 47 is provided with the usual thumb-latch or 10 pawl attachment 54, engaging with sector 51, and holds said lever at any point in the arc of the circle. The lower end of lever 52 is secured in place by the pivot-bolt 55. This lever 52 is also provided with the thumb-latch 15 56, which engages with the toothed sector 57, rigidly secured to a convenient part of the frame. It will be seen that lever 47 has the action of a bell-crank lever when shifted to adjust the reel vertically. This lever 47 has 20 an independent movement with reference to lever 52.

The reel-shaft is normally in the vertical position illustrated. Now by throwing lever 52 forward the reel-shaft is correspondingly 25 tilted on its pivot—the rocking bracket 36. The object of this arrangement is to enable the operator to bring the reel into proper position for stalks that may be inclined or leaning, and it will be observed that by a proper 30 handling of the compound levers the reel may be adjusted to any position within the range of its limit. These compound levers are located back of and in line with the reel-shaft, and for this reason are not shown in 35 Fig. 1, (except the bifurcated end of lever 47,) in order to avoid confusion.

The lever 58 (see Figs. 1 and 3) is located to the right of the driver's seat and extends forward to the front of the machine, where it 40 connects with one end of the rock-shaft 59, (see Figs. 1 and 3,) the opposite crank end of said shaft connecting with the upper end of the link-connection 60, the lower end of which is in turn secured to the draft-pole, as shown 45 in Fig. 1 and broken away in Fig. 2. This lever is provided with the thumb-latch 61, Fig. 3, engaging with the sector 62, which provides for the usual locking adjustment. The purpose of lever 58 is to provide for the tipping or tilting of the machine, as may be necessary 50 in accordance with the undulating surface of the ground and the height of the stalks.

The outer or front end of counter-shaft 21 55 is provided with the double crank 63, (see Figs. 1 and 2,) to which are attached in different planes the connecting-rods 64 and 65. The opposite ends of these connecting-rods are respectively attached to the upper and 60 lower sickle-bars 66 and 67, lying close together, as shown in Figs. 1, 3, and 5. These sickle-bars have suitable supporting-bearings and are provided with the triangular cutting-knives 68. By this arrangement the sickle-bars are adapted to have an alternate reciprocating movement, thus forming a double sickle-bar. The sickle-bars are retained in

proper relative position by the cap-plate 69, provided on the front edge with the overlapping flange 70, Fig. 5, bolted to the frame, and 70 the angle bed-plate 71, also bolted to the frame. A sprocket-wheel 72 is mounted on counter-shaft 21, (see Figs. 1 and 2,) adjacent to the double crank. A second sprocket-wheel 73 is mounted vertically above the first 75 one on the stud-shaft 74, Fig. 1, journaled in the frame. A third sprocket-wheel 75 is located off to one side and mounted on the under roller-shaft 76. (Also shown in Figs. 6 and 7.) A fourth sprocket-wheel *a* is journaled below the third wheel. The link belt B connects this series of sprocket-wheels and transmits the required motion from the driving sprocket-wheel 72. The gear-wheel 77 is mounted on the stud-shaft 74 and engages 80 with the companion gear-wheel 78, mounted on the stud-shaft 79. The sprocket-wheel 80 is also mounted on shaft 79. The companion sprocket-wheel 81 is mounted on the upper roller-shaft 82. (Also shown in Fig. 6.) By 85 means of the link belt 83 the required motion is transmitted to the upper driving-roller 84, on which runs the upper endless apron 85. The larger companion roller 86, over which the apron 85 runs, is mounted on 90 the shaft 87. The lower or carrying apron 88 is supported by and runs over the terminal rollers 89 and 90, 91 being a guide-roller. The respective ends of the upper roller-shaft 95 95 82 are journaled in the upper corresponding 100 ends of the movable frame-boards 92 and 93, located at the front and rear sides of the machine, as more particularly shown in Figs. 6 and 7. The front end of the roller-shaft 82 rests in the elongated aperture 94 in the front 105 part of the main frame, (see Fig. 1,) and is retained in its lowest position by means of the spiral spring 95, inserted in said aperture above the shaft, whereby the roller will yield in an upward direction from any pressure on 110 the under side and be automatically returned to its lowest or normal position when such pressure is relaxed. The ends of shaft 87, on which roller 86 is mounted, are journaled in the respective lower ends of the movable 115 frame-boards 92 and 93. By this arrangement the carrying-rollers, on which apron 85 is mounted, yield in an upward direction, so as to provide for the passage of the stalks 120 that are carried through between the aprons, 120 the upper apron serving to keep the stalks in a compact form and prevent them from working up over the machine until discharged onto the binding mechanism. The pin 96 (see Fig. 6) is inserted in the movable frame-board 92 125 near the lower end and projects through the elongated aperture 97 in the main frame to the front side, as shown in Fig. 1. One end of the plate-spring 98 rests on the front projecting end of pin 96, the opposite end of 130 said spring being rigidly secured to the main frame. The adjusting-screw 99 provides means for regulating the tension of spring 98. The pin 96 and spring 98 provide for the

automatic adjustment of the front end of roller 86. The respective ends of the elliptic spring 100 are attached to the outer side of the rear movable framing-board 93, (see Fig. 5 7,) the back of the spring bearing against the under side of the seat-board 101. This construction provides for the proper working and adjustment of the upper apron and rollers, on which the same is mounted, and for 10 yielding in an upward direction in accordance with the thickness of the object passing underneath and between the aprons, thereby maintaining the required tension on the lower or carrying apron and keeping the 15 same "taut."

102 represents the different parts of the binding mechanism, which is attached to one side of the machine, as shown in Fig. 1, motion being transmitted to the same from 20 sprocket-wheel 75.

As there is nothing new to be claimed in the binding mechanism, a detailed description of the same is omitted.

The curved brace 103 serves to strengthen 25 and stiffen the seat-supporting part of the frame.

The stalks of corn pass in between the dividing-boards, and as they are cut by the double-acting sickle-bars drop onto the lower 30 apron, which at the receiving-point extends beyond the plane of the upper apron, and are carried under the roller 86 and between the aprons to the terminal point of the same and dropped onto the binding mechanism, from 35 which they are finally discharged in bundles. The endless aprons are provided at intervals on their contacting surfaces with a number of transverse cleats 104, which assist in moving along the stalks and prevents the fabric 40 from shrinking or doubling inwardly from the edges.

Having thus described my invention, what I claim as new, and desire to secure by Letters Patent, is—

45 1. In a corn-harvester, the combination, with the driving-shaft, of the clutch mechanism mounted thereon, the bevel gear-wheel rigidly mounted on the loose member of the clutch-box, the counter-shaft 21, the bevel- 50 pinion mounted on the inner end thereof and engaging with said bevel gear-wheel, the bevel gear-wheel 32, mounted on counter-shaft 21, near its outer end, the pinion 33, engaging with gear 32, the shaft 34, on one end of which 55 said pinion is mounted, the opposite end being provided with a gimbal-coupling, the companion shaft 35, provided with a corresponding coupling, the rocking bracket 36, in which shaft 35 is journaled, the tumbling-rod 40, connecting shafts 34 and 35, the bevel-pinion 42, mounted on the outer end of gimbal-shaft 35, the reel-shaft, the bevel gear-wheel mounted on the lower end of the reel-shaft and engaging with pinion 42, and the reel mounted on and 60 rotating with its shaft, and also having a vertical adjustment thereon, substantially as and for the purpose set forth.

2. In a harvester, the combination of the vertical reel-shaft carrying the bevel-wheel 43, the bracket 36, pivoted to suitable lugs or 70 bearings on the frame and supporting the lower end of the reel-shaft, and the shaft 35, journaled in said bracket and carrying the bevel-pinion meshing with the bevel-wheel on the reel-shaft, substantially as described. 75

3. In a harvester, the combination of the vertical reel-shaft, the bracket 36, in which the lower end of the reel is stepped, said bracket pivoted to suitable lugs on the machine-frame, the reel-driving shaft 35, journaled in the upper part of said bracket and carrying a bevel-pinion meshing with the bevel-wheel on the reel-shaft, and the tumbling-shaft 40, whereby the shaft 35 is driven 80 from the counter-shaft, substantially as described. 85

4. In a corn-harvester, the combination, with the reel and its shaft, of the collar loosely mounted on the reel-hub, the angle-lever 47, the toothed sector 51, to which hand-lever 47 90 is pivoted, the companion hand-lever 52, pivoted at its lower end and having the sector 51 secured thereto, the sector 57, and the lock-latches attached to said levers, substantially as and for the purpose set forth. 95

5. In a harvester, the combination of the front sill 8, the continuous plate 69, fastened to its upper edge, the T-iron plate 71, secured to its front vertical face, and the cutter-bars 66 67, working upon the horizontal flange of 100 the T-iron plate and abutting at the rear against its vertical flange, and the plate 69 being flat on its under side and overhanging the upper cutter-bar, and having the lip 70 depending in front of the upper cutter-bar, 105 substantially as described.

6. In a harvester, the combination of the counter-shaft 21, having the sprocket-wheel 72 on its end, the stud-shaft 74 on the elevator-frame and independent of the apron-carrying rollers, the sprocket-wheel 75 on the upper roller 76 of the lower carrier-apron, the stud-shaft 79 on the elevator-frame, also independent of the apron-carrying rollers, intermeshing gears 77 and 78, mounted, respectively, on the stud-shafts 74 and 79, the sprocket-wheel 81 on the shaft 82 of the upper roller of the overlying carrier, the endless belt 83, whereby the shaft 82 is driven from the sprocket-wheel 80 on the stud-shaft 79, and 110 the separate belt B, whereby the sprocket-wheel fixed to the gear 77 and the sprocket-wheel 75 are driven from the counter-shaft, 115 substantially as described.

7. In a corn-harvester, the combination, 120 with the upper roller-shaft 82, carrying the sprocket-wheel 81, of the movable frame-boards 92 and 93, the elongated aperture 94, in which rests the front end of shaft 82, the spiral spring inserted in said aperture and 125 bearing on said shaft, the sprocket-wheel 80, independent of the carrier-apron rollers, and the chain 83, connecting the wheels 80 and 81, 130 substantially as and for the purpose set forth.

8. In a corn-harvester wherein the front side of the elevator is closed by a board, as 8, and the rear side is open, as shown, the combination, with shaft 87, on which roller 86 is mounted, of the frame-boards 92 and 93, the pin 96, inserted in the movable frame-board 92, the plate-spring 98, resting on the projecting front end of said pin, and the elliptic

spring 100, attached to the rear framing-board 93, whereby the apron-roller 86 is adapted to yield in an upward direction, substantially as and for the purpose set forth.

HARRY L. JONES.
